ATTORNEY'S

UNITED STATES PATENT OFFICE.

ERASTUS N. BATES, OF PORTLAND, OREGON, DEDICATED, BY MESNE ASSIGNMENTS,
TO THE CITIZENS OF THE UNITED STATES.

GRAIN ASPIRATOR.

Application filed September 12, 1924. Serial No. 737,368.

(GRANTED UNDER THE ACT OF MARCH 3, 1883; 22 STAT. L. 625.)

To all whom it may concern:

Be it known that I, ERASTUS N. BATES, a citizen of the United States, and an employee of the Department of Agriculture of the United States of America, residing at 5 Portland, Oregon (whose post-office address is 519 Post Office Building, Portland, Oregon), have invented a new and useful 10 Grain Aspirator, of which the following is a full and clear description.

This application is made under the act of March 3, 1883, chapter 143 (22 Stat., 625), and the invention herein described and claimed may be used by the Government of 15 the United States or any of its officers or employees in the prosecution of work for the Government or any person in the United States without payment to me of any royalty thereon.

20 The object of my invention is to provide a device which may be attached to a normal threshing machine for the purpose of removing from the threshed grain, light and small particles of foreign matter which have 25 not been removed by the threshing machine in its normal threshing operation.

The nature, characteristic features, and scope of my invention will be more readily understood from the following description 30 taken in connection with the accompanying drawing, forming a part thereof, wherein:

Figure 1 is a side view of the device showing the relation of parts when attached to a threshing machine elevator; Figure 2 35 is a vertical cross-section of what I shall hereafter term the aspirator head; Figure 3 is a vertical cross-section of what I shall hereafter term the collecting chamber; Figure 4 is a top view of the distributing cone 40 on which the grain falls from the thresher elevator; Figure 5 is a vertical cross-section through the center of the distributing cone showing the flexible pivot connection at the center of the cone; Figure 6 is a side 45 view showing the aspirator head connected directly to the suction fan without using the collecting chamber.

50 Referring to the drawings, A represents a cylinder at the top of which is riveted a tapering connection V, which runs smoothly into a circular cylinder for a pipe connection N. Inserted through this connection member V is a vertical pipe O. Below the

cylinder A, is attached a frustum of an irregular circular cone U which connects 55 the small circular opening M with the cylinder A. Intersecting the long side U¹ of the cone U, is a portion of an irregular circular cone K so placed that its circular open base K² is concentric with the cylinder 60 A. The portion of cone K extending beyond its intersection with cone U is removed leaving an opening B, allowing the free passage of air through this cone K to the inside of the cylinder A. Attached to the 65 upper edge K² of cone K by means of sheet metal straps I¹ is the plate I. Attached over the center of the plate I by means of a loosely fitted rivet H, is the low inverted right cone F. The base of cone F 70 is approximately equal in diameter to the diameter of plate I. The level of cone F is approximately equal in diameter to the 75 diameter of plate I. The level of cone F may be adjusted to any position within the limits of its movement by means of two rods G, spaced 90 degrees apart, flexibly attached to cone F, penetrating plate I and made temporarily fast to cone K by thumb screws W. In the opening B where the short elements of cone K intersect cone U, and at the lower portion of cylinder A, is 80 placed an inverted V-shaped piece of metal L, so arranged that grain will not lodge between the cones K and U but will be conducted through cone U around the side of cone K to the opening M in cone U. A 85 pipe M¹ is secured at the opening M, the function of which is to convey the cleaned grain to hopper or other receptacles (not shown).

Figure 3 consists of a pipe C, connected 90 by the frustum of a right circular cone C¹ to pipe Y. Pipe C is capped by an annular-shaped plate C² through which passes the pipe Z extending to a point below the opening T in pipe T¹. In pipe Y 95 are placed two valves P each consisting of an elliptical plate hinged along the minor axis, the top half of plate being suitably secured to said pipe by either rivets or solder. The lower half of this elliptically-shaped plate is free to swing on its hinge P¹ and is automatically held in a closed 100 position by the adjustable weights Q.

D represents suitable centrifugal exhaust- 105 er connected by pipe T¹ either directly to the opening N of the aspirator head as

shown in Figure 6 or to the expansion chamber opening T and thence by a similar size pipe Z from opening in S to opening at N in the aspirator head as shown in Figure 1. Located in the pipe T¹ is a butterfly valve E so constructed that it can be clamped in any desirable position.

The structural parts constituting my device may be constructed of any material which is sufficiently strong and durable to withstand the strain of operation to which it may be subjected. I prefer to construct the parts of galvanized iron about No. 24 gauge. The rigid connections should be riveted and all connections should be approximately air tight. In connecting the different parts of the device it is usually desirable to use universal elbows in the piping in order to allow more flexibility. The relation of the various parts of the invention are as follows:

The aspirator head is attached to the pipes J containing the grain elevator by a clamp O¹; the grain spout M¹ for receiving the cleaned grain is attached to the aspirator opening M. The source of air suction is connected to aspirator head at clamp N. Figure 1 shows the method of attaching the expansion chamber or pipe C so that the material removed from the wheat will be removed from the air before the air reaches the exhauster D. Figure 6 shows a method of attaching the aspirator directly to the exhauster D in which case the material removed from the grain will be drawn through the exhauster D, and may be either discharged into the threshing machine (not shown) or into the air, by means of a pipe S¹ attached to exhauster D, or a cyclone collector (not shown), may be attached in such a way as to collect the material which may be placed in a suitable receptacle.

In operation the invention works as follows:

The threshed grain is delivered from the thresher elevator in pipes J into the aspirator head at O, the centrifugal effect of the grain motion throwing it practically onto the center of the distributing cone F, the grain collects on this cone until it naturally flows over the edge of the cone F and is collected in the cone U which conducts it to the grain spout M¹ through the opening in M. As the grain flows off the pile collected on the inverted cone F, in a stream made of even thickness by adjusting level of cone F, a current of air enters the aspirator head at B flowing through the cone K and passing into the cylinder A, through the opening made by the plate I and the circular base K² of cone K, passing upward through the thin circular sheet of falling grain, lifting out the light particles which continue with the air through the opening in N, the grain falling through the upward

moving air is not diverted from its course, the air carrying the light particles removed from the grain passes down the vertical connecting pipe Z into the expansion chamber C. The inertia of the material particles carry these particles beyond and out of the current of air which makes a reversal of the direction in the expansion chamber in order to pass out through the pipe T¹ to the exhauster fan D. The particles of material thus removed from the air collect on top of the upper valve P, located in cylinder Y of the expansion chamber C. When sufficient weight of particles have collected on the upper valve P, a slight opening of this valve causes the air suction pressure to be removed from the under part of the upper valve P and become effective at the lower valve P, holding that valve tightly closed. With the removal of the suction pressure from the upper valve P the weight of material readily opens this valve by swinging on hinge P¹ and it drops through the opening onto the top of the lower valve P, the weight Q of the upper valve P now automatically closes the upper valve P and the weight of the material on the lower valve P slightly opens the valve permitting the air suction pressure to be again transferred to the upper valve P. This suction pressure being removed, the weight of the material on the upper part of the lower valve P forces this valve open and the material drops into any suitable receptacle (not shown). Thus by the alternate action of these two automatic valves P, the collected material is removed from the expansion chamber C without releasing the suction in the system. The amount of suction which determines the cleaning effect of the aspirator is controlled by the throttle E. This permits the operator to increase or decrease the cleaning effect as may be deemed desirable from the appearance of the cleaned grain and the material removed. The operation of my device requires power to drive the exhauster D, which provides the source of air suction. My invention has no moving parts except the automatic valves P in the expansion chamber C and the adjustment features E and G mentioned above. Once adjusted to a constant threshing condition, the device requires no further attention until a new adjustment of valve E is desired. By the simple adjustment of valve E the whole range of cleaning possibilities of the aspirator is attained.

From the foregoing it is thought that the construction, operation, and many advantages of the herein-described invention will be apparent to those skilled in the art without further description and it will be understood that various changes in the size, shape, proportion and minor details of construction may be resorted to without departing

from the spirit or sacrificing any of the advantages of the invention.

I claim:

A grain aspirator, consisting of a chamber through which the grain to be treated may flow, a shallow inverted cone in said chamber for the reception and temporary retention of the grain and over which the grain may flow, a grain spout at the lower portion of said chamber for the discharge of the grain, an air inlet opposite said spout and in communication with said chamber, means for causing a flow of air through said air inlet and through the grain as it falls over the sides of said cone, a pipe affixed at 15 the top of said chamber adapted to receive dust and light particles removed from the grain and to permit of the passage therethrough of the current of air, an expansion chamber in the lower portion of said pipe, 20 means for connecting said pipe with a blower, means for collecting said dust and light particles in the lower part of said expansion chamber, and damper means for discharging said dust and light materials from 25 the bottom of said expansion chamber without interrupting the flow of air.

ERASTUS N. BATES.
